UNITED STATES PATENT OFFICE

2,587,932

OVERBOARD DISCHARGE CHUTE

James Dennis Vining, New Orleans, La.

Application July 25, 1950, Serial No. 175,710

2 Claims. (Cl. 114—221)

1

This invention relates to the class of ship supplies and more particularly to a device for use in connection with the discharge outlets for cooling water, waste and the like which extend through the skin of a ship.

In the construction of ships it is necessary to place outlets through the skin of the ships and on each side thereof. These outlets carry off cooling water from the engines and generators, waste from the sanitary system, and the fluids that are pumped from the holes and bilges. When ships are alongside docks or piers, unless these holes are covered the water is projected onto the dock. Likewise, in the case of a ship at anchor such discharge will be projected out onto the decks of small boats that may be brought alongside the ship. In most countries there are strict laws enforced whereby these discharge outlets must be covered in such a way that the water falls harmlessly down the side of a ship and not onto the dock. Accordingly, most ships carry some form of chute, and the former art devices consist of different types of chutes which are constructed of wood with lead weights attached to the bottom to withstand the pressure of water. Others consist of a canvas bag with pockets in the lower ends which, when filled with water become self-weighting. However, each of these forms of discharge chutes are quite unsatisfactory since they are both bulky and difficult to handle, difficult to position over the discharge outlet due to the overhang of the main deck over that portion of the hole through which the discharge outlet extends, and because the prior art chutes permit flow of water or other fluids in an improper manner due to the improper engagement between the chute and the skin of the ship. Therefore, it is a further object of this invention to provide magnetic means for urging a chute into engagement with the skin of a ship.

A further object of this invention is to provide novel means for securing a magnetic member in a casing of a chute so as to be sufficiently waterproof so as to afford proper operation thereof.

Still another object of this invention resides in the provision of novel means for suspending a casing forming an overboard discharge chute which suspension means includes means for transmission of current to magnetic means urging the casing into engagement with the skin of a ship.

Still further objects of the invention reside in the provision of an overboard discharge chute that is strong, durable, highly efficient in oper-

2

ation, simple in construction and manufacture, light in weight, and which will require but one man to lower and to place, the overboard discharge chute being also relatively inexpensive to manufacture.

These, together with the various ancillary objects of the invention which will become apparent as the following description proceeds, are attained by this overboard discharge chute, a preferred embodiment of which has been illustrated in the accompanying drawings, by way of example, wherein:

Figure 1 is a perspective view of the overboard discharge chute shown in operative relation against the hole of a ship;

Figure 2 is an enlarged vertical sectional view as taken along line 2—2 in Figure 1;

Figure 3 is an enlarged horizontal sectional view as taken along line 3—3 in Figure 2;

Figure 4 is an enlarged sectional detail as taken along line 4—4 in Figure 3;

Figure 5 is a detail view showing the construction of the members used in supporting the casing.

With continuing reference to the accompanying drawings wherein like reference numerals designate similar parts throughout the various views, reference numeral 10 generally designates the hull of a ship which is formed from heel plates which are welded or riveted together to thus form a magnetic skin. Extending through this skin are discharge outlets 12 through which cooling water from the engines or generators of a ship or the waste may flow. To prevent this waste from splashing onto a small boat which may be borne alongside the ship or to splash onto a dock or pier there is provided the overboard discharge chute which includes a casing 14 having a front wall 16, side walls 18 and a top wall 20. The casing 14 is open at the rear and at the bottom thereof and the casing may be of any desired configuration so as to conform with the contours of the ship's hull. Extending through the casing and more particularly through the front wall 16 thereof is a U-shaped iron core member 22 which is provided with a pair of parallel legs 24 and 26. Received on the legs 24 and 26 are coils 28 which are encased within a suitable housing 30. The coils are waterproofed by any convenient means and are electrically operatively conducted to a source of electrical power on the ship.

For supporting the casing 14 at the desired location there is provided L-shaped hook members 32 which embrace the casing 30 of the coils 55 and which extend up to form an arcuate eye

portion 34 through which cables 36 are secured. The cables 36 are secured to a junction member 38 which junction member is supported by a flexible rubber covered line 40 having a strength member 42 forming the core thereof about which conductors 44 are wrapped. The strength member 42 is connected to the annular ring 46 in the junction member 38 and likewise lines 48 and 50 which are connected to the casing have their strength members 52 and 54 respectively connected to the ring 46. The conductors 56 and 58 of lines 48 and 50 are connected to the coils 24 and 26 respectively. Any suitable switch means may be provided for controlling the flow of current through the coils 28 on the source of power supply within the ship.

Since from the foregoing the construction and advantages of this overboard discharge chute are readily apparent, further description is believed to be unnecessary.

However, since numerous modifications will readily occur to those skilled in the art after a consideration of the foregoing specification and accompanying drawings, it is not intended to limit the invention to the precise embodiment shown and described, but all suitable modifications may be readily resorted to which fall within the scope of the appended claims.

Having described the invention, what is claimed as new is:

1. An overboard discharge chute comprising a casing open at the rear and the bottom thereof adapted to overlie a discharge outlet extending through the skin of a ship, means to suspend said casing overlying the discharge outlet, and magnetic means carried by said casing for urg-

ing said casing towards the skin of the ship, said magnetic means including a U-shaped core having a pair of substantially parallel legs and a central connecting portion, said legs extending through said casing, said central connecting portion overlying a portion of the front wall of said casing, and coils for inducing magnetic flux in said core carried by said legs.

2. An overboard discharge chute comprising a casing open at the rear and the bottom thereof adapted to overlie a discharge outlet extending through the skin of a ship, means to suspend said casing overlying the discharge outlet, and magnetic means carried by said casing for urging said casing towards the skin of the ship, said magnetic means including a U-shaped core having a pair of substantially parallel legs and a central connecting portion, said legs extending through said casing, said central connecting portion overlying a portion of the front wall of said casing, and coils for inducing magnetic flow in said core carried by said legs, said means to suspend said casing also including means to supply current to said coils.

JAMES DENNIS Vining.
